[57] CLAIM

The ornamental design for an automatic fish feeder, as shown and described.

DESCRIPTION

FIG. 1 is a front elevational view of an automatic fish feeder showing our new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The electrical cord in FIGS. 1, 2, 5 and 6 is shown broken away for indeterminate length.
